Attorney

UNITED STATES PATENT OFFICE.

ARTHUR BOTTOM, OF VETERAN, ALBERTA, CANADA.

AUTOMOBILE SWITCH LOCK.

Application filed January 22, 1923. Serial No. 614,214.

To all whom it may concern:

Be it known that I, ARTHUR Bottom, a citizen of Canada, residing at Veteran, in the Province of Alberta, Dominion of Canada, have invented certain new and useful Improvements in Automobile Switch Locks; and I do hereby declare the following to be a full, clear, and exact description of the invention, such as will enable others skilled in the art to which it appertains to make and use the same.

This invention relates to new and useful improvements in switches, and particularly to locking switches for automobile ignition systems.

One object of the invention is to provide a switch of this character, in combination with an automatic cut-out, whereby the owner of an automobile may open the circuit, by means of a series of switch arms, it being necessary to so position the arms, with respect to a combination dial, on the instrument board of the automobile, that all of the arms will contact with a metallic ring or plate, before the circuit will be completed.

Another object is to provide a switch having a plurality of contact arms and contact plates, the arms being so formed, with respect to their cross-sectional areas, that when all of the arms are engaged with the contact plates, current will flow through the circuit and the cut-out, but when one or more of the arms are not in contact with the plates, the area of the contacted arm or arms will be so small that the resistance will prevent the flow of sufficient current to permit the successful operation of the automobile.

Other objects and advantages will be apparent from the following description when taken in connection with the accompanying drawing.

In the drawing:

Figure 1 is an elevation of the invention, in connection with a fragment of the instrument board of an automobile.

Figure 2 is a view of the opposite side of the dial, showing the metallic rings and the contact and insulated points, together with the switch arms and the automatic cut-out.

Figure 3 is a vertical sectional detail view on the line 3—3 of Figure 2.

Referring particularly to the accompanying drawing, 10 represents a portion of the instrument board of an automobile, on

which is secured the casing 11, having the dial 12 in the outer portion thereof, and a metallic disk 12', secured to the rear face thereof. On the outer face of the dial are formed circular series of letters and numbers, over which are arranged to travel the arms 13, 14, and 15, each having on its outer end a handle or knob 16. These arms are carried by the respective shafts 17, 18, and 19, which are disposed in telescoped relation through the center of the dial. On the inner ends of the shafts 17, 18, and 19, respectively, are fixed the switch arms 20, 21, and 22, said switch arms being arranged to travel on the face of the before-mentioned metallic disk 12'. This disk, however, is divided into two ring portions, arranged in concentric relation, and joined together by the web 23, as seen in Figure 2, and on the face of each ring portion are series of insulated plates 24, the inner ring portion having a single bare space 25, while the outer ring portion has two bare spaces 26. The spaces 26 are out of line with the space 24, and with each other.

The ignition circuit is not shown, but the wires leading thereto are represented by the numerals 27 and 29. The wire 27 is connected with the outer ring portion while the wire 29, is connected to the shafts 17, 18, and 19, as shown in the drawing, in Figure 2.

The switch arms 20, 21, and 22 are so proportioned, in their cross-sectional areas, that when they all contact with the bare spaces of the disk 12', the current will flow freely over the circuit, but should any one of the switch arms be disposed in contact with an insulated plate 24, the combined cross-sectional areas of the switch arms which are in contact with the disk 12', will be too small to permit the current to flow freely, with the result that the resistance offered by the contacting arms will render the ignition circuit inoperative, and prevent the operation of the engine.

It will, of course, be understood that the bare spaces of the disk 12' correspond to certain letters and numbers on the dial, thus permitting the owner to so rotate the arms 13, 14, and 15, as to dispose them over the proper letters and numbers, to position the corresponding switch arms on the bare spaces of the disk.

In some types of automobiles the circuit is grounded to stop the engine, and in this

2
instance the present switch would be applicable thereto by substituting for the insulating plates 24, metal conducting plates and for the conducting portions or spaces 5 25 and 26, insulating plates would be used. Thus when the switch arms are properly set they will be in contact with the insulating plates, and when improperly set will be in contact with the bare spaces, which are 19 grounded.

What is claimed is:

1. A permutation switch including metallic contact points and insulation points, and a plurality of switch arms, the arms 15 and contact points adapted to be included in an electric circuit, said arms being so proportioned with respect to their resistance that absence of one in a circuit will reduce the flow of current.
2. A permutation switch in the circuit and including a contact member and movable switch arms, the said switch arms being proportioned with respect to their cross-

sectional areas that all thereof must engage the said contact member to permit the maximum flow of current. 25

3. A permutation switch in the circuit and including a dial, a metallic plate mounted on the dial and divided into concentric rings in metallic connection, said 30 rings having bared and insulated spaces, shafts disposed through the dial, manually operable arms on one end of the shafts and switch arms on the other end, the latter arms being arranged to traverse the rings 35 and being so proportioned with respect to their cross-sectional areas that absence of one from the circuit will prevent a maximum flow of current.

In testimony whereof, I affix my signature, 40 in the presence of two witnesses.

ARTHUR BOTTOM.
